WALTER N. CRAFTS, OF OBERLIN, OHIO.

ELECTRIC FURNACE.

1,114,733.

Specification of Letters Patent.

Patented Oct. 27, 1914.

Application filed November 28, 1911. Serial No. 662,822.

To all whom it may concern:

Be it known that I, WALTER N. CRAFTS, a citizen of the United States, residing at Oberlin, in the county of Lorain and State of Ohio, have invented a certain new and useful Improvement in Electric Furnaces, of which the following is a full, clear, and exact description, reference being had to the accompanying drawings.

10 This invention relates to electric furnaces of the induction type. In such furnaces it has been customary to provide an induction coil, the primary of which carries alternating current and the secondary of which consists of an annular horizontal bath of the material to be fused. In such furnaces the bath is of inconvenient restricted form; the capacity is limited; it is difficult to work the furnace and to obtain proper circulation of 15 the metal being fused; there is a large surface exposed to scorification, and repairs are difficult. Another disadvantage is the comparatively low power factor, due to the distance between the primary winding and the 20 secondary, which is necessary on account of the heat of the secondary.

The object of my invention is to obviate these difficulties and produce an electric induction furnace of large capacity, with an 25 unrestricted bath, easily worked and repaired, and having a high power factor. In accomplishing this I provide a secondary circuit consisting only partly of fusible material within the bath, the remainder being 30 outside of the bath and made of highly conductive material, which will not fuse in the operation of the furnace. To this end I make the external portion of the conductor of greater conductivity than the bath, so 35 that the current does not heat it to the fusing point.

My invention comprises such a furnace broadly considered and also the more particular embodiment thereof illustrated in 40 the drawings and hereinafter described.

In the drawings, Figure 1 is a side elevation of an open hearth furnace of the cradle type, embodying my invention; Fig. 2 is a vertical section of the same; Figs. 3 45 and 4 are horizontal sections, respectively, through the bath and the cores of the induction device; and Fig. 5 is a vertical section through one of the cores,—the planes of these sections being indicated by the correspondingly numbered lines in Fig. 2.

In the drawings, 10 represents the furnace

body, which is of suitable refractory material (as magnesite, for example) surrounded by the metallic shell 11 and provided with an arched roof 12. 13 designates the basin of this furnace, which is shown as carrying an open bath 14. Above the top line of the bath are the charging openings 15 and 16 on the end and sides of the furnace, these openings being adapted to be 65 closed by suitable doors 17 and 18.

19 indicates the pouring spout connecting through the tap opening 20 with the chamber normally above the bath.

The body above described is shown as 70 mounted on cradles 25, which rest on rollers 26 on suitable supports 27. This enables the furnace to be tipped, as desired, to pour the molten metal through the opening 20.

30 indicates two magnetic cores of the induction device. These cores are of laminated form and mounted horizontally below the furnace body and connected at their ends by yokes 31. As shown, the cores are supported by having their yokes 31 rest on 80 brackets 32 secured to the cradle. As shown, these brackets are insulated from the cradle, being mounted with interposed insulation 33.

35 indicates the primary winding about the cores 30.

36 indicates a metal member which lies beneath and onto the two opposite sides of the primary windings and extends up into the furnace body so that its upper ends are in contact with the bath 14. This metal member 90 is shown as of a double or multiple U-shape to accomplish this result, having a leg 37 on the outer side of each coil and a leg 38 of double width between the two coils. This member 36 is shown as resting on the 95 insulation 33. With the conducting material in the bath, it constitutes two annular secondaries of the induction coil.

Now when an alternating current passes through the primary winding, the two annular secondaries, including the solid metal member 36 and the material in the bath between the upper ends of the legs, becomes heated. By making the member 36 of a material which is of higher conductivity than the material in the bath between the legs, I am enabled to fuse the bath without fusing this external portion of the secondary. For example, if the external secondary member 36 be made of copper, its electric resistance 105 may be many times less than that of the material of the bath between the upper ends 110

- of the copper legs, with the result that there may be an induced current sufficient to fuse the bath without fusing or even unduly heating the external portion of the secondary. The external portion of the secondary below the furnace body may be exposed to the air and thus ventilate and cool itself by radiation. The portions of the legs 37 and 38 within the bottom of the body I prefer to cool artificially. For this purpose I have shown each of these legs as enlarged where they pass through the body and having embedded within them coils 40 through which a cooling liquid may pass. I have shown these coils all connected at one end with a common pipe 41 and at the other end with a common pipe 42, one of these pipes being an intake pipe and the other the exit for the cooling liquid.
- 20 50 indicates suitable plates in the walls of the furnace on opposite sides of the bath, which are terminals of branches of either the primary or secondary circuit, or otherwise supplied with current, and may operate to heat the bath and slag by resistance. It is to be understood that the width of the bath is properly selected so that the desired resistance to the passage of current is obtained.
- 25 30 In starting my furnace, either molten metal or finely divided metal, such as drillings or turnings, is placed in the bath sufficiently to bridge the distance between the legs 37 and 38 of the external secondary, and the current through the primary is started. This establishes a current through the exposed portion of the secondary and the internal portion bridging between the legs, and this fuses the internal portion
- 35 40 without unduly heating the external portion. Additional material to be reduced, melted or refined is supplied from time to time to the bath through the doors, until the bath is completely melted and refined to
- 45 50 the desired extent, when the furnace is tipped to discharge the contents in the usual manner.
- 55 My furnace has many advantages, some of which have been heretofore alluded to. For example, the bath is of large capacity, is of convenient shape, easy to work and similar to the open hearth bath with which workmen are familiar. The form of the bath reduces to a minimum the extent of its slag line, which is subjected to scoriafication. When repairs have to be made the same can be very easily done. In such repairing, if necessary, the entire furnace body can be elevated from the cradle and the trans-
- 60 65 former core and primary windings may be used in a newly repaired furnace, while the old body is being repaired. The entire slag line can be repaired while the furnace is hot. Another advantage is that, with my furnace, the largest part of the heat is pro-

duced above the magnet and primary winding, so that they do not suffer from the effects of the heat, nor is cumbersome ventilation of them necessary. Because the copper legs forming the outside portion of the secondary are cool they can be placed very close to the primary, thus producing a very high power factor. The greatest heat is produced at the bottom of the hearth and hence better circulation of the molten metal is obtained, as well as a great reduction in the loss from radiation. With my type of furnace, banks and roof can be made very high to permit a great amount of slag and foaming, which occur in those processes of refining steel where a large per cent. of ore is used. With my furnace, there is an entire freedom from electrode troubles, as well as the saving in the cost of electrodes, as compared with the arc type of furnace.

Changes and alterations may be made in the construction and arrangement of the parts shown, as will be readily understood. Making the external solid secondary in the double U-shaped form is effective and satisfactory for either single phase or two phase current. Where three phase current is used this multiple member preferably has an additional intermediate leg of the same character as the intermediate leg shown. I have mentioned making this external U-shaped member of copper, though it is to be understood that other metals of relatively high conductivity may be employed, if desired.

Having thus described my invention, what I claim is:

1. In an electric furnace, the combination, with a basin, of an induction coil having an incompletely annular solid secondary portion exterior of and below the basin cooperating with a bottom portion of the bath in the basin to make a completely annular secondary.
2. In an electric furnace, the combination, with a basin, of an induction coil having an unfused incomplete secondary exterior of the basin and terminating at the bottom of the basin and adapted to be completed by fused material within the basin.
3. In an electric furnace, the combination, with a basin, of a magnetic core, a primary winding, and an unfused incomplete secondary having terminals at the bottom of the basin and adapted to be completed by means of a portion of the bath within the basin.
4. In an electric furnace, the combination, with a basin, of a magnetic core outside of the basin, a primary winding, and an incomplete secondary having terminals at the bottom of the basin and adapted to be completed by means of a portion of the bath within the basin, said secondary exterior of the basin being of material of relatively

- high conductivity and hence remaining unfused in the operation of the furnace.
5. In an electric furnace, the combination, with the basin, of a primary, an incompletely annular solid secondary terminating at its upper end in the bottom of the basin and adapted to be completed by molten metal within the basin.
6. In an electric furnace, the combination, with a furnace basin, of a core and primary winding beneath it, and a U-shaped conductor extending about such winding and passing through the bottom of the furnace body and terminating adjacent to the bottom of the basin, said U-shaped member being of relatively high conductivity as compared with the material in the basin.
7. In an electric furnace, the combination of a furnace body having a basin, a U-shaped metallic member of relatively high conductivity beneath the basin and having its upper end extending through the body into position adjacent to the bottom of the bath, a core, and primary winding about the core between the legs of such member.
8. The combination, with a furnace basin, of a U-shaped solid metal member exterior of the basin and having its ends terminating at the bottom of the basin, and a primary winding located in proximity to such U-shaped member, the U-shaped member and fusible material within the basin forming an annular secondary.
9. In an electric furnace, the combination, with a furnace basin, of a core and primary winding, and a solid U-shaped conductor extending about such winding and passing through the furnace body into electric contact with the bottom of the bath, said conductor exterior of the body being exposed for cooling by radiation.
10. The combination, with a furnace basin, of a U-shaped metal member exterior of the basin and having its ends terminating at the bottom of the basin, a primary winding located in proximity to such U-shaped member, the U-shaped member and fusible material within the basin forming an annular secondary, and means for cooling the ends of the legs of such U-shaped member.
11. The combination, with a furnace body, of a U-shaped metal member beneath the body having its legs extending through the bottom of the body, said member being of relatively high conductivity and not fused in the operation of the furnace, a core extending transversely between the legs of the U-shaped member, and a primary winding on such core.
12. The combination, with a furnace body having a basin, of a metal member made in a U-shape and having its legs extending through the bottom of the furnace body into electric connection with the basin contents,
- means for cooling such legs where they pass through the body, a horizontal core beneath the body and between the legs, and a primary winding on such core.
13. The combination of a furnace body having a basin, a metal member made in double-U-shape having three solid extending legs terminating within the furnace basin, magnetic cores on opposite sides of the central leg of said member, and primary windings on such cores occupying the two U-portions of the member. 70
14. The combination, with a furnace basin, of a double U-shaped solid metal member exterior of the basin and having its ends terminating at the basin, an annular magnetic member occupying the two bends of the member first mentioned, and a primary winding about such magnetic member. 75
15. The combination of a furnace body having a basin, a solid metal member made in double-U-shape having three extending legs terminating within the furnace basin, magnetic cores on opposite sides of the central leg of said member, primary windings on such cores occupying the two U-portions of the member, and means for cooling the metal legs within the furnace body. 80
16. The combination, with a furnace body having a basin, a solid U-shaped metal member having its legs embedded in the furnace body, the upper ends of the legs being exposed at the bottom of the basin, cooling coils within such legs in the body, a transverse core between the legs, and a primary winding around such core. 85
17. In an electric furnace, the combination, with a body, of a support therefor on which the body removably rests, a solid U-shaped metal member carried by the body and depending from it, the legs of the U terminating within the basin carried by the body, a transverse core beneath the body, and a primary winding for said core. 90
18. In an electric furnace, the combination of a body having a basin, an incompletely annular copper member having solid legs terminating adjacent to the bottom of the basin, said member with fusible material in the basin constituting an annular conductor, and a primary winding making an induction coil with such annular conductor. 95
19. The combination, with a furnace body having a basin, of a multiple U-shaped member beneath the body having legs extending through the bottom of the body into electric connection with the basin contents, cores beneath the body lying between the legs, the interior leg or legs being of larger cross section than the outside legs, and primary windings around such cores. 100
20. The combination, with a furnace body having a basin, of a multiple U-shaped member beneath the body having legs extending

through the bottom of the body into electric connection with the basin contents, cores beneath the body lying between the legs, primary windings around such cores, the 5 legs being enlarged where they extend through the body, and cooling coils embedded in such legs.

21. The combination, with a furnace body having a basin, of a multiple U-shaped solid 10 member of relatively high conductivity depending from the body and having its surface exposed for radiation, and having legs extending through the bottom of the body into electric connection with the basin contents, and cores and primary windings beneath the body lying between the legs, the 15 outer legs being of less cross section than

the intermediate leg or legs and the legs being internally cooled where they pass through the furnace body.

20

22. The combination, with a furnace basin, of an induction coil having a core, a primary winding and an annular secondary located in an up and down plane and consisting of a portion of a continuous molten bath in 25 the bottom portion of the basin, and a continuous solid conductor terminating at its upper end at the bottom of said bath.

In testimony whereof, I hereunto affix my signature in the presence of two witnesses. 30

WALTER N. CRAFTS.
